UNITED STATES PATENT OFFICE.

FREDERICK W. LINAKER, OF DUBOIS, PENNSYLVANIA, ASSIGNOR, BY MESNE ASSIGNMENTS, TO THE VULCAN SOOT CLEANER CO., OF DUBOIS, PENNSYLVANIA, A CORPORATION OF DELAWARE.

SOOT-CLEANER FOR WATER-TUBE BOILERS.

1,279,382.

Specification of Letters Patent. Patented Sept. 17, 1918.

Application filed November 12, 1915. Serial No. 61,101.

To all whom it may concern:

Be it known that I, FREDERICK W. LINAKER, a subject of the King of England, residing at Dubois, in the county of Clearfield and State of Pennsylvania, have invented certain new and useful Improvements in Soot-Cleaners for Water-Tube Boilers, of which the following is a specification.

This invention relates to certain new and useful improvements in soot cleaners for water tube boilers.

The present invention has particular reference to water tube boilers that have associated with the banks of tubes, baffle plates that extend parallel with the tubes and arranged adjacent the same. In boilers of this character, it has heretofore been found impossible to position a cleaning fluid distributing pipe adjacent the water tubes without breaking the continuity of the baffles, and in so doing the gases and products of combustion passing from the furnace box into the heating chamber will be permitted to escape through the openings in the baffles and pass from the furnace without all of the heat in the gases and products of combustion having been utilized, and also without having passed over the entire surfaces of the water tubes. Realizing the disadvantage of providing the clearance openings in baffle walls for the positioning of cleaning fluid distributing pipes, the present invention aims to negative the loss of heat in the wasted gases and products of combustion and provides housings or coverings for the cleaning fluid distributing pipes wherein the housings or coverings are preferably supported by the baffle plates and close the openings therein that provides clearance for the distributing pipes.

The particular construction of the distributing pipe and its mode of operation does not enter into the details of the present invention, as the same may be a rotary distributing pipe or a stationary distributing pipe, but the form shown is substantially that which is shown in patent granted to E. Los E. Hibner and F. W. Linaker, #1,144,543, dated June 29, 1915.

It is also to be noted that the present invention may as well be applied to a vertical or semi-vertical water tube boiler of the

Stirling type as well as a horizontal water tube boiler.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

Fig. 1 is a longitudinal sectional view of a portion of a water tube boiler of the horizontal water tube type with the present invention applied thereto, illustrating the lower and upper baffle plates, with the housings or coverings for the fluid distributing pipes associated with the upper baffle plate.

Fig. 2 is a cross-sectional view of a portion of a vertical water tube boiler of the Stirling type that includes baffle plates with the present invention applied thereto.

Fig. 3 is a longitudinal sectional view of a portion of the boiler setting with the housing or covering for the distributing pipe shown in section, and

Fig. 4 is an enlarged detail cross-sectional view of one of the housings or hoods for the distributing pipe, there also being shown a portion of the baffle wall and a water tube with the cleaning fluid distributing pipe positioned between the same in cross-section.

Referring more in detail to the accompanying drawings, and particularly to Fig. 1, the reference numeral 10 designates a boiler setting of any preferred construction having positioned therein the horizontal water tubes 11 positioned directly above the fire chamber. In order that the gases and products of combustion from the fire chamber may pass completely over and engage all of the tubes 11, there is provided a lower baffle wall 12 that is supported in any preferred manner adjacent the water tubes 11 and extends from the front ends thereof to a point adjacent the rear ends as is indicated. An upper baffle plate 13 is supported in any preferred manner adjacent the upper water tubes 11 and extends from the rear ends of the tubes to a point adjacent the front ends thereof so that

1,278,382

the gases and products of combustion passing from the fire chamber will contact the lower baffle wall 12 and travel toward the rear ends of the water tubes 11 to pass completely over and contact the same and further to be directed by the upper baffle plate 13 in a direction toward the front ends of the water tubes.

Cleaning fluid distributing pipes are arranged within the boiler setting 10 and are 10 preferably positioned adjacent the upper ones of the water tubes 11 and also in proximity to the upper baffle plate 13. A preferred form of distributing pipe is shown in Fig. 3 and is designated by the numeral 14,

15 the said pipe passing through one side of the boiler setting 10 as at 15 and having the closed inner end thereof received in a socket or recess 16 at the opposite side of the boiler setting. Cleaning fluid distributing nozzles

20 17 are carried by the distributing pipe 14 and are desirably spaced relative to the water tubes 11 so that soot and other coatings on the boiler tubes may be removed by action of the jets of the cleaning fluid agent

25 from the nozzles 17. The form of distributing pipe shown is of the rotary type although the same might as well be of the stationary type without in any manner affecting the gist of the present invention, and

30 as shown, the outer projecting end of the distributing pipe is provided with a toothed wheel 18 over which a chain 19 or other driving means passes and by which the distributing pipe is revolved. The operating

35 chains are shown in dotted lines in Fig. 1 and have been omitted from Fig. 3. In order to further support the distributing pipe 14, there are provided clamp members 20 that are detachably connected to upper ones

40 of the boiler tubes 11 while the said clamp members carry journal collars 21 through which the distributing pipe extends, this construction being more clearly shown in Fig. 3.

45 The piping system for feeding the cleaning fluid agent to the distributing pipes 14 includes a main supply 22 having a controlling valve 22' the main supply pipe 22 communicating with the feed pipe 22" which in turn communicates with the distributing pipes by means of the branch pipes 23, there being provided a controlling valve 24 for each branch pipe as well as drain cocks 25 for the main supply and feed pipes.

50 55 The distributing pipe 14 is preferably connected to the branch pipes 23 by fluid-tight swivel connections to enable the distributing pipes to be revolved with danger of the cleaning fluid agent escaping, obviated.

60 65 In positioning the distributing pipes adjacent the upper row of water tubes 11, it is necessary that openings or clearance spaces be provided in the upper baffle plate 13. Unless these openings are in some manner cov-

will escape therethrough and fail to pass completely over the tubes, and in the present instance the form of covering or hood is shown more clearly in detail in Figs. 3 and 4.

As shown in Fig. 3, the hood 26 is formed of a plurality of interlocking sections 26' that are curved or arch-shaped in cross-section while the lower side edges 27 rest upon the upper row of water tubes with the curved portions thereof spaced from the cleaning fluid distributing pipe 14 as is indicated. It is not necessary that the hood 26 be formed in sections as shown in Fig. 3 but may be constructed in any suitable manner to meet the required conditions. At the extreme rear end of the upper baffle plate 13 there is provided an opening that is of a width substantially equal to the width of the hood 26 as is shown in Fig. 4, and the hood is lowered into the opening to span the same and cover the distributing pipe 14. At the point where the lower side edges 27 of the hood 26 rest upon the water tubes 11 and engage the side walls of the hood opening, the same may be sealed as by plastic cement or other suitable material indicated by the reference numeral 28 so that in reality the continuity of the upper baffle plate 13 is not disturbed. The central portion of the upper baffle plate 13 is broken away to provide a clearance for a pair of cleaning fluid distributing pipes 14 that are arranged adjacent each other and in this instance a pair of hoods 26 are utilized, the adjacent lower side edges 27 of the hoods contacting each other while the outer lower side edges engage the sides of the opening in the baffle plate. The hoods in this position also rest upon the upper row of tubes 11 while a sealing material such as liquid cement before 105 mentioned seals the joint between the baffle plate and the outer side edges of the hoods as at 28 while the inner contacting side edges are sealed as is indicated by the reference numeral 29. Substantially this same form of combined hood construction is positioned at the extreme forward end of the baffle plate 13 and is mounted in a similar manner above the tubes and cleaning fluid distributing pipes. The form of hood herein shown is 110 a preferred form of construction but the same may take any desired form without departing from the gist of the present invention, and it is also to be noted that the material from which the hood is constructed may be made of any heat resisting material.

The invention is equally applicable to a vertical water tube boiler or semi-vertical water tube boiler wherein any baffle plates extend parallel to the banks of tubes and this adaptation of the invention is shown in Fig. 2 wherein the boiler setting 10 includes the semi-vertical tubes 30 having the baffle wall 31 positioned adjacent the same and extending parallel thereto. In this construction of 125

130

boiler, the baffle plate 31 is provided with a pair of spaced openings that are covered by hoods 26' similar to the ones referred to in connection with Fig. 1 while the cleaning fluid supply system is also identical as is indicated by the branch pipes 23 and while the present invention is shown as applied to horizontal and semi-vertical water tube boilers, it is not intended that the present invention should be limited thereto as the same may be readily applied to any boiler including tubes or flues and wherein there is provided a baffle plate extending parallel to the flues.

15 While the forms of the invention herein shown and described are what are believed to be the preferred embodiments thereof, it is nevertheless to be understood that various forms, modifications and arrangements 20 of the parts may be made without departing from the spirit and scope of the invention as claimed.

What I claim as new is:—

1. A soot cleaner including a cleaning fluid distributing pipe, discharge nozzles carried by the pipe, a hood for the pipe slightly spaced therefrom to provide a clearance for the nozzles, and a baffle having an opening therein for the reception of the 30 hood.

2. A soot cleaner including a cleaning fluid distributing pipe, a baffle plate having a clearance opening therein for the pipe, and a hood associated with the baffle plate 35 overlying the plate opening and pipe.

3. A soot cleaner including a cleaning fluid distributing pipe arranged adjacent boiler tubes, a baffle plate having a clearance opening therein for the reception of 40 the pipe, and a hood spanning the clearance opening and covering said pipe.

4. A soot cleaner including a cleaning fluid distributing pipe arranged adjacent boiler tubes, a baffle plate resting on the 45 upper row of tubes having a clearance opening for the pipe, and a hood received in said

plate opening and resting on said tubes overlying the pipe and sealing the plate opening.

5. A device of the class described, including boiler tubes and a baffle plate arranged parallel thereto, said plate having openings therein, cleaning fluid distributing pipes arranged in said openings, and hoods spanning the openings overlying the pipes. 50

6. A device of the class described, including a baffle plate having a cleaning fluid distributing pipe clearance opening intermediate the ends thereof, a cleaning fluid distributing pipe arranged therein, and a hood 60 spanning said opening.

7. A soot cleaner including a baffle plate interrupted intermediate its ends, cleaning fluid distributing pipes associated with the interrupted portion of said baffle plate, a 65 pair of coöperating hoods associated with said interrupted portion of the plate and covering said pipes, the said hoods having abutting side flanges and sealing means for the joints between the baffle plate and hoods. 70

8. A device of the class described, including a baffle plate interrupted intermediate its ends, a cleaning fluid distributing pipe located at the interrupted portion, and means associated with the plate for restoring 75 the continuity thereof and overlying the pipe.

9. A device of the class described including a baffle plate arranged substantially parallel to boiler tubes, said plate being interrupted intermediate the ends thereof, a cleaning fluid distributing pipe located at the interrupted portion, and means associated with the plate for restoring the continuity thereof and providing a hood for 85 the pipe. 80

In testimony whereof I affix my signature in presence of two witnesses.

FREDERICK W. LINAKER.
